INVENTOR
JULIUS JUDELSON
BY
Maurice F. Finkelman
ATTORNEY

UNITED STATES PATENT OFFICE.

JULIUS JUDELSO, OF NEW YORK, N. Y.

WASHBOARD.

Application filed December 20, 1920. Serial No. 432,151.

To all whom it may concern:

Be it known that JULIUS JUDELSO, citizen of the United States, and resident of the city of New York, in the county of Bronx 5 and State of New York, has invented certain new and useful Improvements in Washboards, of which the following is a specification.

This invention relates to wash-boards. 10 One object thereof is to provide a device of the character described which shall have a rubbing surface adapted to effectively cleanse the clothes without subjecting the latter to any sharp edges or corners that 15 may cut or otherwise harm the clothes or the hands of the operator.

Another object is to provide a device of 20 this type which shall be simple in construction, cheap to manufacture, and efficient in operation.

Other objects of this invention will be in part obvious and in part hereinafter pointed out.

The invention accordingly consists in the 25 features of construction, combinations of elements and arrangement of parts which will be exemplified in the construction hereinafter described and of which the scope of invention will be indicated in the following claim.

In the accompanying drawings, in which is shown one of various possible illustrative embodiments of this invention,

Fig. 1 is a front elevation of a wash-board 30 embodying this invention;

Fig. 2 is an end elevation thereof showing the wash-board inclined in the position it takes in the wash-tub;

Fig. 3 is a horizontal cross-section through 40 the rubbing surface taken along line 3—3 of Fig. 1;

Fig. 4 is an enlarged detailed sectional view similar to Fig. 3 of a portion of the rubbing surface; and

Fig. 5 is an enlarged partial vertical elevational view of the rubbing surface.

Referring in detail to the drawing, the washboard embodying my invention there shown, is seen to comprise a head piece 10 and side rails 11 between which extends the rubbing plate 12 hereinafter more particularly to be described. The said rails 11 preferably extend beyond the rubbing plate so as to provide legs 13, 13' for supporting

the wash board in the tub, as will be readily understood.

The construction of the rubbing board 12 will now be described in detail. This consists of a plate 14 preferably of metal on which are embossed rubbing elements 15 preferably in the form of smooth convexly curved ring portions 16 upstanding from the plate. To give stiffness to these raised portions 16, the metal is curved downwardly in the reverse direction, that is, concavely from these convex portions, resulting in a ring 17 concentric with the ring 16 as will be readily understood, and smoothly continuous therewith, as at 17. In constructing the wash-board in practice, these rubbing elements 15 are struck from the metal preferably by a die and simultaneously with the formation of the concentric rings 16 and 17 there are formed concentric therewith the perforations 18. These perforations serve to allow the water to drip through the rubbing board into the tub while the clothes are being washed. Further, the water in the tub is enabled thereby to come in contact with the clothes both from the inside thereof and the side facing the operator.

In the formation of the rubbing elements in the manner hereinbefore described, there is a sharp edge 19 forming the periphery of the perforation as will be readily understood. The counter-sunk concave rings 17 prevent the clothes or the hands of the operator from coming into contact with this sharp edge, while the convex rings 16 provide the necessary rubbing surface for cleansing the materials.

In the embodiment shown in the drawing the head piece 10 and side rails are formed continuous with the rubbing board 12, the latter being suitably bent to provide the 95 head piece 20 and rectangularly as at 21 to provide the side rails. For giving stiffness to the side rails, bars 22 are inserted into the hollow rectangular portions 21 as is clear from Fig. 3. At the base of the rubbing board in the rear portion thereof, is a horizontal stiffening bar 23 for giving strength thereto. For further strengthening the frame, vertical bars 24 are secured in a suitable manner on the rear face of the 105 board adjacent the side rails 11 as will be clear from said figure.

The head piece 20 is provided with a suit-

able soap holding ledge 25 bent rearwardly from the rubbing board 12, the rear upstanding wall of said head piece 20 being disposed in a plane at an acute angle with 5 respect to the said plate. Said head piece 20 is constructed to have its upper edge overturned to form a rounded bearing surface for contacting with the operator's body and to form a transverse brace for the device. 10 (See Figs. 1 and 2.) Thus the head piece 20 provides a soap holding means set back from the front of the rubbing board 12 so as not to interfere with the washing operation, and the rear side of the ledge 25 may engage over the rim of the tub (not shown) 15 to serve as stop means for retaining the wash board in position.

The bottom of the legs 13, 13' may further be provided with rubber padding 26 to 20 prevent the legs from injuring the walls of the tub.

It will thus be seen that there is provided apparatus in which the several objects of this invention are achieved and which is 25 well adapted to meet the conditions of practical use.

As various possible embodiments might be made of the above invention and as various changes might be made in the embodiment above set forth, it is to be understood 30 that all matter herein set forth or shown in

the accompanying drawings is to be interpreted as illustrative and not in a limiting sense.

Having thus described my invention, I 35 claim as new and desire to secure by Letters Patent:—

In a wash board construction, a frame comprising side and cross members, a rubbing plate secured to the frame, a plurality of uniformly spaced rubbing elements being formed on said plate, stiffening means formed integral with the outer edges of said rubbing plate, said means comprising a head piece, bottom and side portions, said bottom 45 and side portions being bent about the frame, said head piece being bent rearwardly of the rubbing plate to form a soap holding ledge, then upwardly, the upstanding wall of said head portion being disposed in 50 a plane at an acute angle with respect to the rubbing plate, and the upper edge of said wall being overturned to form a rounded bearing surface, said ledge shaped to overhang the rear side of the board to serve 55 as a stop means to retain the wash board in position.

Signed at New York city, in the county of New York and State of New York, December A. D. 1920.

JULIUS JUDELSOHN.
